UNITED STATES PATENT OFFICE

2,612,046

THERMOMETER

John J. Crawley, Scarsdale, N. Y., assignor to Wm. H. Wise & Co., Inc., New York, N. Y., a corporation of New York

Application November 9, 1949, Serial No. 126,358

1 Claim. (Cl. 73—352)

1

The present invention relates to thermometers, and more particularly to thermometers embodying a thermometer tube secured to a back plate carrying suitable scale indicia and perhaps other information, the invention having particularly to do with improved means for securing the tube to the back plate.

Objects and advantages of the invention will be set forth in part hereinafter and in part will be obvious herefrom, or may be learned by practice with the invention, the same being realized and attained by means of the instrumentalities and combinations pointed out in the appended claim.

The invention consists in the novel parts, constructions, arrangements, combinations and improvements herein shown and described.

The accompanying drawings, referred to herein and constituting a part hereof, illustrate an embodiment of the invention, and together with the description, serve to explain the principles of the invention.

Of the drawings:

Fig. 1 is a front elevation of a typical and illustrative embodiment of the invention;

Fig. 2 is a cross-sectional view taken along line 2—2 of Fig. 1; and,

Fig. 3 is a cross-sectional view taken along line 3—3 of Fig. 1.

The object of the invention is the provision of an improved thermometer of the type comprising a tube and a back plate to which the tube is secured, the invention providing means for securing the tube to the plate which are strong and of relative simplicity, and may be applied to provide a clean and efficient final assembly without damage to the porcelain covering of the back plate and with relative economy.

In the illustrative embodiment of the invention herein shown and described by way of example, there is provided a thermometer tube of any suitable and conventional type and a back plate therefor which carries calibrations in degrees of heat and perhaps other information which might be useful in cooking, for instance, the particular embodiment of the invention herein disclosed being adapted for use in the roasting of meats. Clasps are provided for clamping across the tube to hold it to the back plate, and the clasps are held to the plate by means of rivets passing through the plate. The plate is pierced to provide apertures to receive said rivets, and such piercing is done from the front surface toward the rear of the plate, whereby annular, integral raised portions are produced at the back of the

plate surrounding the apertures. The rivets are preferably of a type in which at least a portion of the length is hollow adjacent one end, and this end is positioned at the rear surface of the plate and peened over the raised annular portions just mentioned.

Referring now in detail to the embodiment of the invention shown in the drawings, a thermometer tube 10 is provided having its lower end encased in a conical metallic end piece 11 whereby the tube may be inserted conveniently into meat or other food while cooking, if desired. The back plate 12 is formed as shown of metal to receive the tube 10 and carry suitable indicia 13 from which indicated temperature may be taken. The tube 10 is preferably provided with an extension 14 (dotted lines Fig. 1) adapted to be received within an aperture 15 in plate 12 to prevent relative movement of the tube and plate when finally assembled, which would destroy accuracy of the instrument.

The tube 10 is centrally positioned on the back plate 12 and securely held thereto by means of one or more U shaped clasps 16, each said clasp comprising a curved extent 17 to engage the surface of tube 10, and a pair of plane end portions 18 adapted to seat on the front surface of plate 12. The clasps 16 are held in position by means of rivets 19, as best shown in Fig. 2 of the drawings. Said units pass through a suitable aperture in each of the clasp end portions 18, and through registering apertures 20 in back plate 12.

As shown, the apertures 20 in the back plate are most efficiently and economically formed by piercing the back plate from the front surface thereof toward and through the rear surface, and in this operation the displaced material forms an annular extension 21 about each aperture 20 out of the plane of the rear surface of the back plate 12 and integral with the back plate. The back plate is provided with a coating of vitreous enamel 22 covering all exterior surfaces of it as completely as possible, and the tube 10 is thereafter secured in place.

The rivets 19 are provided with heads 23 which are adapted to seat on the plane portions 18 of clasps 16, and the opposite ends of the rivets are positioned at the rear surface of plate 12 and preferably have a central bore 24 sufficient to allow easy peening over of the rivet. As shown in Fig. 2, the assembly is completed and fixed in place by spreading or peening over the hollow rivet ends in portions 25, on the raised annular portions 21 at the back surface of the plate 12. Applicant thus provides a thermometer as-

sembly the parts of which are securely held in place and which is neat in appearance and sanitary for continued use and cleaning. The provisions of annular extensions 21 at the rear surface of plate 12, and assembly of the instrument as described, protects the vitreous coating 22 from damage. The rivet heads 23 are seated on plane portions 18 of clasps 16 which are in turn seated on the front enameled surface of plate 12, and this broadly distributes the forces created during riveting and protects the coating 22 from undue stresses. Furthermore, the annular portions 21 above the rear surface of the back plate upon which spreading takes place in affixing the rivets provides a strengthened structure in the plate where force is applied, serving to localize the effects of pressure, prevent undue flexing of the plate and possible cracking of the coating 22. The coating 22 tends to pull away from places where edges are presented in back plate 12, and this is true of the edges of annular portions 21, so that the turned ends 25 of the rivets are positioned both to cover and protect these edges and to be applied where a coating is very thin or not present at all. The described construction results in further economies in fabricating the instrument, as the apertures 20 may simply be pierced and no further smoothing or finishing operation is necessary. In the event that the edges of the annular extensions 21 are rough or uneven, they may be flattened and covered by rivet end portions 25 when the rivets are affixed.

The invention in its broader aspects is not limited to the specific mechanisms shown and described but departures may be made therefrom, within the scope of the accompanying claim, without departing from the principles of the invention and without sacrificing its chief advantages.

What I claim is:

A thermometer comprising, in combination, a thermometer tube, a vitreous enamel covered back plate to carry said tube, said plate having front and rear surfaces and a pair of apertures one at either side of said tube, said apertures being formed by piercing said plate from the front to the rear surface thereof providing integral annular portions of material displaced from said plate, said annular portions surrounding the apertures and extending outwardly from the rear surface of said back plate, a clasp of thinner material than the back plate for securing said tube to said back plate comprising a curved central extent engaging said tube and plate, said clasp having apertured end portions one at either end thereof seated on the front surface of the back plate, the apertures therein registering with respective ones of said apertures in said back plate, and a pair of rivets each having a solid head seated on a respective one of said clasp end portions, passing through said apertures and having hollow ends at the rear of said back plate spread and seated on respective annular back plate portions, the spread rivet ends being turned over and downwardly on said integral annular back plate portions.
